City, N. J., a corporation of Delaware

Application June 18, 1945, Serial No. 600,185

8 Claims. (Cl. 222—81)

1

This invention relates to devices for puncturing and forming a pouring opening in the wall of a cardboard or the like container.

Devices designed for the purpose of insertion into a wall of a cardboard container in order to form an opening and/or spout for the dispensing of materials from the container are well known.

It is the primary object of my invention to provide a new and improved puncturing and dispensing device particularly designed to be used with a cardboard or the like container, which is easily and cheaply made, of simple construction, and which may be quickly attached to the container or detached therefrom.

Another object of my invention is the provision of an improved puncturing and dispensing device for a cardboard or the like container which is so shaped as to be guided by a wall of the container during insertion and to frictionally engage the same wall to retain the device in the container.

Another object is the provision of an improved device of the kind described which has no portions protruding from the container either during use or when not in use.

It is another object to provide a flat metallic blank of such configuration that when properly bent and formed it will result in a device of the class described.

Other objects will become apparent as the description proceeds in connection with the accompanying drawings, wherein:

Figure 1 is a pictorial view of a cardboard container and one form of the invention applied thereto and ready for use in dispensing material such as soap powder from the container;

Figure 2 is a view in side elevation of the device shown applied to the container in Figure 1;

Figure 3 is a bottom plan view of the device of Figure 2;

Figure 4 is a view along the line 4—4 of Figure 3, looking in the direction of the arrows, and also showing the material of the container with relation to the device when it has been inserted into the container as in Figure 1;

Figure 5 is a front elevation of the device of Figure 2 as seen from the right of Figure 2; and

Figure 6 is a plan view of a metal blank which, when properly folded, forms the device of Figure 2.

As shown in Figure 1, the device generally designated at 10 has been inserted through a side wall 11 of a cardboard container 12 and adjacent the top wall 13 thereof so that an opening 14 is provided in the side wall 11, the top of the

2

opening being adjacent the top wall 13. The device itself, in the illustrated embodiment, is formed from a flat blank 15 shown in Figure 6. A large rectangular flap or guide 16 overlies the top wall 13. The wall 13, plus a flap 17 (Fig. 4), which has been cut from the side wall 11 of the container and remains hinged at its top to the edge of the top wall 13, is clamped between the flap or guide 16 and a ledge 18 which is a continuation of the flap 16. As is apparent from Figures 2, 4 and 6, the ledge 18 is parallel to and slightly spaced from the flap 16, being formed by bending the blank substantially at the portion indicated by the dotted line 19 of Figure 6.

15 A pair of opposed and inwardly inclining side walls 20 and 21 extend downwardly from the ledge 18 and terminate in a pair of inwardly extending pointed flaps 22 and 23 which lie in a plane substantially parallel to the ledge 18 and flap or guide 16. The side walls 20 and 21 are formed by bending the blank substantially at the portions indicated by the dotted lines 24 and 25 of Figure 6, and the pointed flaps 22 and 23 are properly located with respect to the side walls 20 and 21 and the ledge 18 by bending the blank substantially at the portions indicated by the dotted lines 26 and 27 of Figure 6.

The longer sides 28' and 29' of the pointed flaps 22 and 23 abut against each other as best shown in Figure 3 and provide a pointed cutting knife parallel to the flap or guide 16 and pointing in the same direction, away from the line where the flap 16 joins the ledge 18.

A flap 28, which is of substantially triangular shape as shown in Figure 6, extends downwardly from the ledge 18 and forwardly toward the cutting knife as best shown in Figures 2 and 4. The flap 28 is properly located by bending the blank 15 substantially along the portion indicated by the dotted line 29 of Figure 6, which is preferably curved as illustrated in Figures 2 and 4 to facilitate forcing hinged flap 17 upwardly during insertion of the spout. The lowermost or free end of the flap 28 extends substantially to the top of the cutting knife, as shown in Figures 2, 4 and 5. The purpose of the flap 28 is to force the hinged flap 17 upward as the device is inserted into the carton, so that hinged flap 17 will be moved up out of the way and between the ledge 18 and flap 16 as shown in Figure 4. Since it is not the purpose of the flap 28 to obstruct the passage of the material being dispensed from the box, it does not necessarily fill or block the tubular passage formed by the ledge 18, side walls 20 and 21, and the pointed flaps 22 and 23.

While the material could be dispensed solely through the aforementioned tubular passage, the walls of the passage would block entrance thereto except from its end adjacent the cutting knife. Accordingly, an aperture 38 (Fig. 1) is formed through the walls of the said passage adjacent the pierced side wall 11 of the box by the expedient of cutting away a portion of each pointed flap 22 and 23 at the ends thereof which are remote from the cutting knife. Thus, a passageway or spout for the material in the box is formed by the rear edges of the pointed flaps 22 and 23, a portion of the bottom edges of the side walls 20 and 21, and the bottom edge of the opening formed in the side wall 11 of the container 12 by the insertion of the device 10.

In order to insert the device into the container, it is placed on the side of the container with the flap or guide 16 resting flatly on the container top wall 13 and with the point of the cutting knife resting against the outside surface of the side wall 11. While holding the flap or guide 16 against the top of the container, the device is pushed parallel to wall so that the cutting knife pierces the wall 11 and the whole device is pushed further until it has been inserted wholly into the container as shown in Figure 1. It will be frictionally held in the container by the top 13 and the flap 17 which are engaged between the top of the ledge 18 and the bottom of the flap or guide 16. The distance to which the device can be inserted is limited by the engagement of the edge of the top 13 with the fold in the device where the guide 16 joins the ledge 18, as most clearly shown in Figure 4. The dimensions of the device are such that, when it has been fully inserted, the rear portions of the side walls 20 and 21 bear against the sides of the opening 14 formed in the side wall of the container, and prevent the leakage of material from the container between the wall 11 of the container and the side walls 20 and 21 of the device.

It will be observed that the forward and inclined edges of the side walls 20 and 21, as well as the forward and inclined edges of the pointed flaps 22 and 23, are sharpened to form knife edges 31 and 32 as shown in Figure 6, so that as the device is inserted into the container the forward edges of the side walls, as well as the forward edges of the pointed flaps, perform a cutting operation to provide the opening through which the device is inserted into the container.

While the illustrated embodiment of the device is shown made from a blank cut from sheet metal or the like, it is to be understood that it may be formed in other ways as by casting or molding, and that it need not be made of metal but can be made of a plastic material, since the plastic materials are sufficiently hard to be used for cutting through the average cardboard container.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A device for puncturing and cutting a pouring opening in a wall of a cardboard or like con-

tainer during insertion into said container comprising an elongated guide flap; a ledge substantially parallel to said flap and spaced therefrom; means joining the flap and ledge at their adjacent outer ends and providing a stop for engaging the container and limiting insertion of the device into the container, side walls attached to said ledge and extending away from said guide flap; and a bottom wall apertured opposite said ledge joining the bottoms of said side walls, said side and bottom walls having substantially continuous cutting edges along the ends thereof which are remote from the juncture of said guide flap and ledge, and said ledge, bottom and side walls defining a dispensing spout within the container having an exit mount opposite said cutting edges and disposed at the container wall opening formed by insertion of the spout into the container and an entrance opening formed by said aperture in said bottom wall.

2. A device for puncturing and forming a pouring opening in the wall of a cardboard or the like container at a juncture of that wall with a second wall at an angle thereto, comprising an elongated flat guide flap comprising a ledge parallel to said flap and spaced therefrom; means joining the flap and ledge at their outer ends and adapted to engage the container at said juncture to limit insertion of the device into the container, side walls attached to said ledge and extending in a direction away from said guide flap; a bottom wall joining the bottoms of said side walls and having a material admitting opening opposite said ledge and extending inwardly from said exit mouth, said side and bottom walls having continuous cutting edges which are remote from the juncture of said guide flap and ledge, and said cutting edges being inclined to form a pointed cutting knife with the point of the knife being substantially at the center of the bottom wall, and means forming a second flap extending from said ledge toward said bottom wall and away from the juncture of said ledge with said guide flap to lift the flap which has been cut from the wall of the container and which remains hinged at one end to said second container wall.

3. A blank for the manufacture of a device for puncturing and forming a pouring opening in the wall of a cardboard or the like container, comprising a substantially rectangular portion; a substantially triangular portion attached at one side to one end of said portion; and a pair of flaps attached at their sides to the sides of said portion adjacent said one end, said last mentioned flaps having sharp cutting edges diverging outwardly.

4. A device for providing a pouring opening in one of two intersecting walls of a container comprising spout means formed with puncturing and cutting means for penetrating one of said walls and displacing a portion thereof inwardly and toward the inner surface of the other of said walls to form an aperture in said one wall in alignment with said spout, said spout being formed with an exit mouth opposite said cutting and puncturing means and a bottom intake opening within the container, guide means on said spout adapted to slide along the exterior of said other wall when said spout is penetrating said one wall, means joining the guide means and the spout at their outer ends and serving as a stop to engage the container and limit insertion of the device into the container, and cooperating means on said spout and guide means for clamping said displaced wall portion against the interior surface

of said other wall and for maintaining said device on said container.

5. A pouring spout adapted for insertion into a container through one of two intersecting container walls comprising a spout open at its outer end and open laterally adjacent said outer end, a cutter on the inner end of said spout so that when said spout is applied and forced through one of said container walls it cuts away a portion of said one wall, means on said spout for folding said cut away wall portion inwardly about its region of attachment to said container, and means on said spout for embracing said folded portion and the other wall of said container for maintaining said portion folded against the inner surface of said other wall comprising a flap extending over the external surface of said other wall and integrally connected to said spout by an intermediate portion which serves as a stop adapted to engage the container at said intersection to limit insertion of said device into the container and locate the open outer end of said spout at the aperture in the container wall formed by insertion of the spout.

6. A combination container puncturing and cutting device and spout for providing a pouring opening in one of two intersecting walls of a container comprising a spout portion formed at its inner end with a point for puncturing one of said container walls and an inclined cutting edge for following the point and cutting an aperture in said one wall, said spout having an exit mount opening opposite said point and an intake opening in the bottom thereof, means on the spout for folding the cut away portion of said one wall against the adjacent inner surface of the other wall, means on the spout for frictionally embracing said other wall and the folded portion of said one wall adjacent said intersection comprising the top of said spout and a substantially parallel flap adapted to overlie the external surface of said other wall, and means comprising an integral connection between said spout and said flap for engaging the container at said intersection limiting insertion of the spout into the container and positioning the exit mouth of said spout at the wall aperture formed by insertion of the spout and

with the intake opening of said spout communicating directly with the contents of the container whereby when the container is tilted the contents thereof may dispense freely through said spout.

7. The device defined in claim 6 made of a pre-formed blank of bendable sheet metal, and wherein in said flap is a reversely bent integral extension of the top wall of said spout.

8. In a combination container wall puncturing and cutting device and pouring spout, an elongated flat guide flap, and a spout portion having a top wall which is a reversely bent integral substantially parallel extension of said guide flap, side walls integral with said top wall and inclined toward each other from opposite sides of said top wall and a bottom wall substantially parallel to said top wall formed by oppositely bent extensions of the side walls, said spout portion having its exit mount immediately below the reverse bend between said guide flap and the top wall of the spout and having a material admission opening in said bottom wall extending inwardly from said exit mount, and the side edges of said side and bottom walls having continuous sharp edges meeting in a point to provide a container wall cutting and puncturing blade projecting from said spout opposite the exit mouth.

Certificate of Correction

June 6, 1950

Patent No. 2,510,530

WILLIAM F. TELSCHOW

It is hereby certified that errors appear in the printed specification of the above numbered patent requiring correction as follows:

Column 3, line 24, after the word "wall" insert the numeral 13; column 4, line 30, after the syllable "tainer" strike out the comma and insert instead a semicolon; line 56, after the syllable "wardly" and before the period insert *from said rectangular portion*;

and that the said Letters Patent should be read with these corrections therein that the same may conform to the record of the case in the Patent Office.

Signed and sealed this 12th day of September, A. D. 1950.
